United States Patent

Des. 239,419
Patented Mar. 30, 1976

239,419

TAPE CASSETTE STORAGE UNIT

Robert A. Clowe, Penfield, N.Y., assignor to
Xerox Corporation, Stamford, Conn.

Filed Sept. 26, 1974, Ser. No. 509,364

Term of patent 14 years

Int. Cl. D3—02

U.S. Cl. D87—1 D

FIG. 2

FIG. 3

FIG. 4

FIG. 5

FIG. 6

FIG. 1 is a left-hand front perspective view of a tape cassette storage unit showing my new design;

FIG. 2 is a top plan view thereof;

FIG. 3 is a left side elevation view thereof;

FIG. 4 is a right side elevation view thereof;

FIG. 5 is a front elevation view thereof; and

FIG. 6 is a rear elevation view thereof.

I claim:

The ornamental design for a tape cassette storage unit, as shown.
